(57) **CLAIM**

I claim the ornamental design for a deployed integrative meteorological system, as shown and described.

DESCRIPTION

FIG. 1 is a top perspective view of a deployed integrative meteorological system embodying the new design.

FIG. 2 is a first side view of the deployed integrative meteorological system embodying the new design.

FIG. 3 is a second side view of the deployed integrative meteorological system embodying the new design.

FIG. 4 is a top view of the deployed integrative meteorological system embodying the new design.

FIG. 5 is a bottom view of the deployed integrative meteorological system embodying the new design.

FIG. 6 is a third side view of the deployed integrative meteorological system embodying the new design.

FIG. 7 is the third side view of the deployed integrative meteorological system embodying the new design relative to an angled ground surface; and,

FIG. 8 is the second side view of the deployed integrative meteorological system embodying the new design relative to an angled ground surface.

The dashed lines, which may include a ground surface in certain figures, are for illustrative purposes only and form no part of the claimed design.
